(57) **CLAIM**

The ornamental design for a surveillance television camera, as shown and described.

DESCRIPTION

FIG. 1 is a front elevational view of the surveillance television camera showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a perspective view taken from the front, bottom and right side of the surveillance television camera.

The portions of the camera in broken lines are shown for illustrative purposes only and form no part of the claimed design.
